(57) **CLAIM**

The ornamental design for a pool vacuum, as shown and described.

DESCRIPTION

FIG. 1 is a front, right side perspective view of a pool vacuum showing our new design;

FIG. 2 is a bottom plan view thereof;

FIG. 3 is a top plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines in the drawings depict portions of the pool vacuum that form no part of the claimed design.

1 Claim, 6 Drawing Sheets
